US0D1029050S

(12) **United States Design Patent** (10) **Patent No.:** **US D1,029,050 S**
(45) **Date of Patent:** **** May 28, 2024**

(54) **INSULATING DEVICE**

(71) Applicant: **YETI Coolers, LLC**, Austin, TX (US)

(72) Inventors: **Derek G. Sullivan**, Austin, TX (US);
Erik Steven Larson, Austin, TX (US);
Laura Flores, Austin, TX (US); **Alex Baires**, Austin, TX (US)

(73) Assignee: **YETI Coolers, LLC**, Austin, TX (US)

(**) Term: **15 Years**

(21) Appl. No.: **29/881,986**

(22) Filed: **Jan. 9, 2023**

Related U.S. Application Data

(63) Continuation of application No. 29/765,022, filed on Jan. 5, 2021, now Pat. No. Des. 975,141, which is a continuation of application No. 29/703,760, filed on Aug. 29, 2019, now Pat. No. Des. 975,140, which is a continuation of application No. 29/664,260, filed on Sep. 24, 2018, now Pat. No. Des. 862,528, which is a continuation of application No. 29/601,723, filed on Apr. 25, 2017, now Pat. No. Des. 829,244.

(57) **CLAIM**

The ornamental design for an insulating device, as shown and described.

DESCRIPTION

FIG. 1 is a front view of an insulating device showing our new design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The broken lines immediately adjacent to the shaded area represent unclaimed boundaries of the design. The broken lines showing the remainder of the insulating device represent unclaimed stitching, or unclaimed subject matter.

1 Claim, 5 Drawing Sheets
